(57) **CLAIM**

The ornamental design for a ball of foot cushion, as shown and described.

DESCRIPTION

FIG. 1 is a front perspective view of a ball of foot cushion showing my new design;

FIG. 2 is rear perspective view thereof;

FIG. 3 is a front view thereof;

FIG. 4 is a rear view thereof;

FIG. 5 is a left side view thereof;

(Continued)

FIG. 6 is a right side view thereof;
 FIG. 7 is a top view thereof; and,
 FIG. 8 is a bottom view thereof.

1 Claim, 8 Drawing Sheets
